T. A. ROTSCHE

CLAMPING OR SEPARATING DEVICE

Filed May 14, 1925

INVENTOR.
THEODORE A. ROTSCHE

BY *Fred D. Hayn*

ATTORNEY.

UNITED STATES PATENT OFFICE.

THEODORE A. ROTSCHE, OF WHITTIER, CALIFORNIA.

CLAMPING OR SEPARATING DEVICE.

Application filed May 14, 1925. Serial No. 30,280.

My invention relates to a novel form of device or mechanism affording an expeditious and speedy means for clamping certain separated parts together, or optionally separating the same or other parts of said structure.

As is well known in oil well practice, a pump rod frequently fractures so close to its socket or screw-threaded connection associated with the various sections of said rod, that heretofore it has been impossible to remove the broken part from its socket or connection, necessitating the replacement of both rod and socket, and consequently requiring the added expense of said socket, which in most cases is still perfectly good and usable. By the use of my invention these objectionable features are entirely eliminated, it being possible to remove the broken 20 portion of the pump rod in a surprisingly short period of time.

It may also be stated that by the use of my invention it is possible not only to remove fractured pump-rod pins, but is equally useful in removing broken bolts from nuts, forcing cross keys from shafts, and numerous other uses for which said invention is especially adapted.

Another object of my invention is to provide a novel form of device or mechanism, preferably provided with a U-shaped member, one leg of which is equipped with a stationary element in the form of one or more projections extending from said leg, the other of said legs being adapted to have positioned therein by means, for example, of screw-threads, a reversible angular rotary element, which element may be provided with means, such as hollowed-out engaging portions, either end of said element being adapted to be made to coact with said projections to provide an efficient and expeditious means for clamping or separating certain parts of a structure.

A further object of my invention is to provide a novel form of device or apparatus which is simple in form, exceptionally easy and inexpensive to manufacture, durable, almost impossible to get out of order, composed of a minimum number of parts, and thoroughly reliable and efficient to effect the objects intended.

It may also be stated, that it is within the province of my invention to arrange the projections associated with one of the legs of the

U-shaped member out of alignment, so that in case one should be broken the others will still be able to function.

Further objects and advantages of my invention will become more apparent as the description thereof proceeds.

Reference is had to the accompanying drawings in which similar reference characters denote similar parts. In the drawings,

Fig. 1 is a side elevational view of my invention, assembled, and showing the manner in which it is used in practice;

Fig. 2 is a similar view on an enlarged scale of the reversible angular and movable element removed from the U-shaped member;

Figs. 3 and 4 are respectively side and end elevational views of my U-shaped member;

Fig. 5 is a fragmentary part cross-sectional view of Fig. 1 on an enlarged scale but disclosing a slightly modified form of my invention;

Fig. 6 is an elevational view of the connector or socket showing a fractured pump-rod associated therewith;

Figs. 7 and 8 are cross-sectional views respectively on the lines 7-7 and 8-8 of Fig. 2, and

Figs. 9 and 10 show plan and fragmentary elevational detail views of a modification.

Describing my invention more in detail, it is my purpose to construct the bracket or U-shaped member 1 of highly tempered tool steel, one leg 9 of which is bent inwardly as shown to provide for rigidity and stiffness, the end of said leg being equipped with one or more projections 10, shaped as shown, also for the sake of stiffness and rigidity, said projections being preferably, though not necessarily, three in number, as shown in Fig. 4.

The other leg 2 is preferably bent substantially at right angles to the body portion of the member 1, and said leg is equipped with a hole 3, preferably, though not necessarily, screwthreaded to provide an engaging means with the threaded ends 5 and 6 of the angular element or crank portion 4, which element constitutes the active member of my device.

As will be clear from Fig. 2, the ends 5 and 6 are provided with reduced portions 7 and 8 of different diameter, so that sockets, connectors, nuts, and the like, of different diameter may be accommodated. The por-

tions 7 and 8, as shown in Figs. 7 and 8, are also preferably hollowed-out, which hollowed portions are adapted to coact with and form an efficient means for engaging 5 any projections which may happen to be formed on the broken part or other structure to be removed, clamped, or separated.

It may also be stated that the use of three 10 projections, rather than one or two, provides for a much more steady and secure hold on the parts to be removed, clamped, or separated. It has been found in practice that the sharp points on said projections will take into and readily hold any iron or 15 steel of average construction, and the pressure exerted will even hold securely any exceedingly hard or tough metal.

My invention is also exceedingly useful in 20 drawing together parts or articles that have become spread, where such articles or parts 25 cannot be moved by a vise, or said articles or parts when in such form that the more or less wide vise jaws cannot enter the same. As is well known, such contingencies often 30 arise in the handling of machinery, engines, and the like.

As shown in Figs. 1, 5, and 6, my invention 35 is especially useful in connection with the socket or pump-rod connector S, when 40 the pump-rod R has become fractured close to said socket or connector.

In such a case, the socket S is positioned 45 between the legs 2 and 9 of the member 1 so that the broken rod R will be positioned 50 over the projections 10. Depending upon the diameter of the socket S, the appropriate 55 end 7 or 8 is inserted in the hole 3 of the leg 2, and screwed home, said end entering the socket S and engaging with the inner 60 end of the broken rod R, the hollowed portion of said end engaging with any projection that may be present on said rod.

The member 7—4—8 has been fashioned 65 as shown so that by holding the member 1 firmly, either by hand, or in a suitable vise or clamp, the end 8 may be used as a crank 70 to remove the broken portion R from the socket S. The projections 10 engaging the lower portion of the broken portion R, and 75 the part 7 being in firm engagement with the upper part of said broken portion, the threads 5 will engage with the threads of the socket S, when the end 8 is used as a crank, causing the broken portion to be unscrewed from said socket.

As hereinbefore stated, if the socket S has 80 a different internal diameter than that of the part equipped with the threads 5, the

member 7—4—8 is reversed, the threads 6 60 engaging the threads of the socket.

It will be understood, of course, that a wrench may be applied to the socket S, in 65 case said socket is of such a size that the threads 5 or 6 may not be engaged with the threads of said socket. Such a construction 70 is shown in Fig. 5. The parts being in the position previously described, the wrench is applied to a socket and the broken portion R quickly removed thereby.

It will of course be understood that I do 75 not desire to be limited to the exact proportions or shape of the various parts of my invention, nor do I desire to be limited to the exact manner of mounting the angular member 4 in relation to the leg 2, since this 80 in practice may be varied.

While I have thus described my invention 85 with great particularity it will be obvious that the same may be modified throughout a wide range. I therefore do not propose to 90 be limited to the exact details of construction shown and described, but reserve the right in practice to make any and all modifications thereof that fall within the scope 95 of the appended claims.

I claim as my invention:

1. In a device of the class described, a U-shaped member, one or more projections 90 on one of the legs of said member, an angular element equipped with a set of screw-threaded portions associated with the other leg of said member, said angular element when rotated being adapted to coact with 95 said projections to form a clamping means or to separate two devices through the action of said threads.

2. In combination, a U-shaped member, one or more projections on one of the legs of 100 said member, an angular element associated with the other leg of said member, and means on both ends of said angular element whereby either of said ends may be made to coact with said projections to provide optionally a separating or clamping means.

3. In a device of the class described, in 105 combination, a U-shaped member, there being one or more projections associated with one leg of said U-shaped member, and an angular element having a pair of hollow end portions reduced in size, either of which is 110 adapted to be positioned in the other leg of said member for the purpose set forth.

In testimony whereof I have signed my name to this specification.

THEODORE A. ROTSCHE
